UNITED STATES PATENT OFFICE

155,241

DESIGN FOR A BATHING SUIT OR SIMILAR
ARTICLEAlbert L. Sommers and Albert Young,
Newburgh, N. Y.

Application May 3, 1948, Serial No. 146,134

Term of patent 7 years

(Cl. D3—17)

To all whom it may concern:

Be it known that we, Albert Young and Albert L. Sommers, citizens of the United States, residing at Newburgh, in the county of Orange and State of New York, have invented a new, original, and ornamental Design for a Bathing Suit or Similar Article, of which the following is a specification, reference being had therein to the accompanying drawing, forming a part thereof, in which

The essential characteristics of this design, reside in cut-out flowers, each including suspending threads, and an artistic center portion entirely supported by said threads, as shown.

We claim:

The ornamental design for a bathing suit or similar article, as shown and described.

ALBERT L. SOMMERS.
ALBERT YOUNG.
